DEVICE FOR APPLYING PREFORMED SINKERS
TO FISHLINESEdmund J. Czelusniak, Easthampton, and Frederick
R. Belliveau, Chicopee Falls, Mass.

Application October 3, 1957, Serial No. 688,069

2 Claims. (Cl. 1—187)

This invention is directed to new and useful improvements in a fisherman's device and is directed more particularly to improvements in devices for applying preformed sinkers to fishlines.

The principal object of the invention is directed to the provision of a manually operable device for holding a stack of separate preformed crimpable sinkers which incorporates means for crimping successive endmost sinkers of the stack to a fishline or lines.

According to novel features of the invention, the device is provided with a guideway for a stack of separate crimpable sinkers which are preformed with line receiving grooves, in combination with a crimper element for acting on an endmost沉器 of the stack so as to crimp the same about a line in a groove thereof, together with a means for urging the stack of sinkers toward an outlet or discharge end of the guideway from which the crimped沉器 may be withdrawn.

As one feature of the invention, the crimper of the device has an end portion for acting on, in a crimping manner, an endmost沉器 of a stack so as to crimp same onto a line, and it has an adjacent end portion adapted to permit withdrawal of a crimped沉器 which is arranged to be engaged by an uncrimped沉器 adjacent thereto, and to function as a stop for the stack of sinkers.

As another feature of the invention, operating means is provided for reciprocating the crimper element into crimping and stop positions of its crimping and stop portions in combination with a means for moving the crimper to non-crimping position, and a manually engageable means for the operating means.

Some of the advantages of the invention reside in its simplicity of construction, in its efficient and dependable operation, and in its adaptability to economical manufacture.

These together with other objects and advantages of our invention which subsequently will become apparent as the description proceeds reside in the details of construction and operations as more fully hereinafter described and claimed and the features of novelty which characterize the invention will be pointed out with particularity in the claims annexed to and forming part of this specification.

To the accomplishment of the foregoing and related ends, said invention then comprises the features herein-after fully described and particularly pointed out in the claims, the following description and the annexed drawing setting forth in detail certain illustrative embodiments of the invention, these being indicative, however, of but a few of the various ways in which the principle of the invention may be employed.

In the accompany drawing forming a part hereof, we have illustrated a complete example of a physical embodiment of the invention in which the parts are combined and arranged in accordance with one mode which we have devised for the practical application of the

2

principles of the invention. It will be understood however that changes and alterations are contemplated and may be made in these exemplifying drawings and mechanical structures, within the scope of the claims, without departing from the principles of the invention.

In the said drawing:

Fig. 1 is a plan view of a device for applying sinkers to lines and embodying the novel features of the invention.

Fig. 2 is an end elevational view of the device shown in Fig. 1.

Fig. 3 is a plan view of the device shown in Fig. 1 with the cover plate removed.

Fig. 4 is a longitudinal sectional view through the device on the line 4—4 of Fig. 3.

Fig. 5 is an enlarged perspective view of the end portion of the crimper of the device.

Fig. 6 is an enlarged perspective view of a plurality of sinkers; and

Fig. 7 is a perspective view of the retainer of the invention.

In the following description and claims, various details will be identified by specific names for convenience. These names however are intended to be as generic in their application as the art will permit.

Referring now to the drawing forming a part of this specification more in detail, in which similar characters of reference indicate corresponding parts in the several views, and referring more particularly to the preferred form of our invention selected for illustrative purposes, I have shown a combination of elements in order that the general relation and utility of the device may be better understood.

A holder 2 is provided which will be formed from suitable metal to have a body 2' with an upper cover or side plate 4 secured to the upper face thereof by rivets, screws or the like, indicated by 8.

Said body 2' along the upper side thereof has a longitudinal guideway 10 for a stack of separate sinkers, indicated by S. Said sinkers are preformed from lead or other suitable material, and have line receiving grooves S' in a side thereof. The grooves of the sinkers are uppermost and extend longitudinally of the stack and guideway, as shown in Figs. 2 and 3.

The body 2 is provided with an enclosed recess or depression 12. A crimper element 14 is reciprocable along an end 12' of said recess between a non-crimping, and a sinker crimping position. The crimper 14 is shown in non-crimping position in Fig. 3.

The crimper 14 has on its outer end a stop portion 16 which extends forwardly relative to a crimping portion 18 adjacent thereto, and the outer forward face of the stop portion 16 is angularly disposed, as shown in Fig. 5.

With the crimper 14 in the position shown in Fig. 3, the stop portion 16 extends into the guideway and acts as a stop for the endmost沉器 of the stack.

With a line L passing through the groove S' of the endmost沉器 S, the crimper 14 is moved outwardly. The crimping portion 18 presses on and crimps the near side of the said沉器 towards the outer side thereof, to close the groove around the line L, in such a manner that the near side of the沉器 is so formed that it may pass by the angular face of the stop portion 16 of the crimper. The endmost沉器 may be withdrawn outwardly from the guideway, and the next沉器 of the stack abuts the side of the crimping portion of the crimper.

As the crimper then retracts inwardly this next and now endmost沉器 will abut the stop portion 16.

The near side of the endmost沉器 S which is pressed on, and crimped by the crimping portion 18 is shown at 18' in Fig. 6.

A retainer 22 having a flat outer side face 24 is pro-

vided with a shank 26. Said shank is formed with an annular groove 28, and with a flat 30 face in the plane of the bottom of the groove 28. A pin or detent 32 is fixed in the plate which is receivable in the groove 28 of the retainer shank.

The retainer 22 is inserted in a suitable hole, provided in the end of the body, by passing the flat 30 of the shank beneath the inner end of the pin 32. By turning the retainer the pin 32 is received in the groove 28 of the shank whereby the retainer is held against axial displacement from the hole, thereby the spring is under tension, and acts on to urge the stack of sinkers toward the outlet end of the guideway.

The position of the flat 24 of the retainer indicates whether the retainer is properly positioned and held by the pin 32 against displacement. The retainer may be turned and withdrawn, and the spring removed for insertion of sinkers in the guideway.

The plate 4 is provided with an elongated slot 34 therethrough into the outlet end portion of the guideway, and is in parallelism therewith. Said slot facilitates locating a line, represented by L, in the groove of the endmost sinker for crimping said sinker onto the line, see Figs. 4 and 6. The plate 4 at opposite sides of the slot 34 is arranged to overlie opposite sides of the sinkers outwardly of the grooves therein.

An elongated lever 35 in the recess 12 of the body 2' is pivoted at 38 to the body intermediate its ends for swinging in opposite directions. One end of said lever is disposed in a notch 39 provided in a side of the crimpler, as shown in Fig. 3.

An operating member is formed with elongated side arms 40 which are slidably guided in suitable manner on opposite sides of the holder, and have outer adjacent ends connected by a manually engageable portion 42.

The arms 40 are connected as by a pin 44, extending through an opening 46 in the body 2' to an opening 48 in the opposite end of the lever 35.

A spring 50 is interposed between the lever 35 and a side of the recess 12, and urges said lever in clockwise direction so that the crimpler is yieldingly held in non-crimping position, shown in Fig. 1.

In operation the manually engageable member 42 is pressed upon so that the lever 35 is moved against the action of spring 46 thereby to move the crimpler to crimping position, and crimp a line in the groove of the endmost sinker of the stack thereof. When released the lever is swung by the spring to non-crimping position of the crimpler.

It will be noted that an elongated guideway is provided for a plurality of separate preformed sinkers which are provided with line receiving grooves, and that endmost sinkers may be successively crimped about a line or lines.

The body 2' at one corner thereof is cut away at 52 for a ring 54 encircling a rivet 8. Said ring will be convenient for suspending the device from a support, belt or the like.

From the foregoing, the construction and operation of the device will be readily understood and further explanation is believed to be unnecessary. However, since numerous modifications and changes will readily occur to those skilled in the art, it is not desired to limit the invention to the exact construction shown and described.

While we have illustrated and described the invention as embodied in certain specific arrangements, it will be understood by those skilled in the art that the object of the invention may be attained by use of constructions different in certain respects from those disclosed without departing from the underlying principles of the invention.

We do not intend to be limited to the details shown

since various suitable modifications and variations in structural changes may be made without departing in any way from the spirit of the invention. We therefore desire by the following claims to include, within the scope of our invention all such suitable variations, modifications and equivalents by which substantially the results of our invention may be obtained through the use of substantially the same or equivalent means.

Without further analysis, the foregoing is intended to so fully reveal the gist of our invention that others can, by applying current knowledge, readily adapt it for various applications without omitting features which, from the standpoint of prior art, fairly constitute essential characteristics of the generic or specific aspects of this invention, and therefore, such adaptations should and are intended to be comprehended within the meaning and range of equivalence of the claims below.

What it is desired to claim and secure by Letters Patent of the United States is:

1. A device for holding a stack of preformed lead sinkers having line receiving grooves therein longitudinally of said stack and for crimping the endmost sinker of the stack thereof onto a fishline in the groove thereof comprising, an elongated holder having a longitudinal guideway along a side thereof for a stack of separate preformed sinkers having line receiving grooves uppermost thereof along said stack, said guideway having a forward outlet end, a spring in the rear portion of said guideway for urging a stack of sinkers therein forwardly towards said outlet end, a member releasably connected to said holder at a rear end of said guideway for abutting said spring and being removable for insertion of sinkers and said spring in said guideway, an upper portion of said holder adjacent the outlet of the guideway having a slot therethrough into the guideway for insertion of a line into the groove of the endmost sinker of a stack thereof in said guideway, portions of said holder at opposite sides of said slot arranged to overlie opposite upper sides of sinkers in said guideway, said holder provided with a closed recess having an end wall disposed transversely relative to and adjacent the outlet end of said guideway and a side wall, a crimpler reciprocable along said end wall between outer crimping and inner non-crimping positions having a crimping portion and a stop portion at the outer end thereof adjacent the outlet end of the guideway, said holder having a passageway between said recess and guideway for the outer end of said crimpler, said crimping portion being formed in crimping position of the crimpler to engage and press on a side portion of an endmost sinker to crimp the same on a line in the groove thereof, said stop portion adapted to permit the withdrawal of a crimped sinker from the guideway thereunder and arranged as a stop for the sinker of the stack adjacent said crimped sinker, an elongated lever pivoted intermediate its ends in said recess for swinging movements and having one end in operable engagement with said crimpler to reciprocate said crimpler in crimping and non-crimping directions, a manually engageable operating member reciprocably guided on to said holder for movements transversely thereof, and operative connecting means between said member and opposite end of said lever.
2. A device set forth in claim 1 wherein said manually engageable operating member includes relatively spaced elongated arm members and grooves provided on upper and lower sides of the body in which said arm members are slidably.
